UNITED STATES PATENT OFFICE.

CHRISTIAN WILLIAM MEINECKE, OF JERSEY CITY, NEW JERSEY.

DESIGN FOR A WATER-BAG.

SPECIFICATION forming part of Design No. 34,274, dated March 26, 1901.

Application filed February 27, 1901. Serial No. 49,173. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Water-Bag, of which the following is a specification.

This invention relates to a new and original design for water-bags, and is illustrated in the accompanying drawing, in which the figure is a perspective view.

The feature of my new design resides in a water-bag provided with a downwardly pointing or extended bottom, said bag having its width longer or of greater dimension than its height and having a mouth with a cylindrical neck jutting out from the center of its upper edge opposite the point or apex of the bottom.

In the said drawing the water-bag is shown with its bottom having the point a or the downwardly-extended portion projecting below the body or main portion of the bag and gradually tapering to a rounded or dull-point portion.

The mouth b has a cylindrical neck and is located at the center portion of the upper edge of the bag or opposite the apex a.

The body of the bag, as seen, is of greater width than height.

The design presents a water-bag having a novel and pleasing appearance.

What I claim as new, and desire to secure by Letters Patent, is—

The design for a water-bag substantially as herein shown and described.

In testimony whereof I have hereunto set my hand in the presence of two subscribing witnesses.

CHRISTIAN WILLIAM MEINECKE.
